(57) **CLAIM**

I claim the ornamental design for a seating unit frame, as shown and described.

DESCRIPTION

FIG. 1 is a perspective view of a seating unit frame according to the new design shown in its seating unit environment; FIG. 2 is a perspective view of a seating unit frame according to the new design; FIG. 3 is a front view of the seating unit frame shown in FIG. 2; FIG. 4 is a rear view of the seating unit frame shown in FIG. 2; FIG. 5 is a top view of the seating unit frame shown in FIG. 2; FIG. 6 is a bottom view of the seating unit frame shown in FIG. 2; and, FIG. 7 is a right side view of the seating unit frame shown in FIG. 2; the opposed left side view being a mirror image thereof. In the drawings, features in broken lines form no part of the claimed design.
